CHARLES J. AMUNDSON, OF OSSEO, WISCONSIN

VIOLIN GLUING FORM

Application filed August 29, 1931. Serial No. 560,161.

This invention relates to gluing forms for violins, and has for one of its objects to provide a novel device of this character through the medium of which a perfectly shaped violin may be built in a comparatively short time and with comparatively little effort.

With the foregoing and other objects in view, the nature of which will appear as the description proceeds, the invention consists in the construction, combination and arrangement of parts hereinafter fully described and claimed, and illustrated in the accompanying drawings, wherein:

Figure 1 is a view in side elevation of a violin gluing form constructed in accordance with my invention, the sides, back and neck of the violin being shown by broken lines in assembled relation on the form.

Figure 2 is a top plan view of the form with the sides, neck and back of the violin shown in solid lines in assembled relation thereon.

Figure 3 is a sectional view on an enlarged scale taken on the plane indicated by the line 3—3 of Figure 2.

Figure 4 is a sectional view taken on the plane indicated by the line 4—4 of Figure 3.

Figure 5 is a sectional view on an enlarged scale taken on the plane indicated by the line 5—5 of Figure 2.

Figure 6 is a sectional view taken on the plane indicated by the line 6—6 of Figure 5.

Figure 7 is a plan view of one of the clamp blocks of the form, and

Figure 8 is a sectional view illustrating a slightly modified form of the means by which the violin corner blocks are secured to the form.

The form comprises a body 1 having convex upper and lower edge portions 2 and 3, respectively, concave side or intermediate edge portions 4, and shoulders 5 located between the convex and concave edge portions. Due to its convex edge portions 2 and 3 and concave edge portions 4, the body 1 has a contour similar to that of the body of a violin. The body 1 is provided opposite its concave edge portions 4 with openings 6, and is provided opposite its shoulders 5 with openings 7. The body 1 is provided in its upper end

with a recess 8 and in its lower end with a recess 9, and is provided opposite its convex edge portions 2 and 3 with openings 10 and 11, respectively.

The body 1 consists of two longitudinal sections 1a and 1b which are similar and which are secured together with their inner edges in relatively spaced relation. Transverse bars 12 are employed to secure the body sections 1a and 1b in assembled relation, and are secured to the sections by screws 13. The body sections 1a and 1b are provided with transverse grooves 14 for the reception of the bars 12, and the bars are provided between their ends with lugs or extensions 15 which are located between the body sections. The body sections 1a and 1b are provided with screw threaded recesses 16 for the reception of the screw 13, and the bars 12 are provided with openings 17 through which the screws freely pass.

The recesses 14 of the body sections 1a and 1b, and the lugs 15 of the bars 12, cause the bar openings 17 to register with the body section recesses 16 on the assembling of the body sections and bars, and thus adapt the body sections and bars to be assembled and secured together easily and quickly. A longitudinal bar 18 is secured to the transverse bars 12 and extends above the upper end of the body 1, and the extension 18a thereof is inclined similar to the neck of a violin. The longitudinal bar 18 is secured to the transverse bars 12 by screws 19 which pass freely through openings 20 of the longitudinal bar and engage in screw threaded recesses 21 in the transverse bars. The transverse bars 12 and the longitudinal bar 18 are provided with interengaging recesses 22 and 23, respectively, which enable the longitudinal bar to be readily placed upon the transverse bars in a manner to register the openings 20 with the recesses 21. The recesses 14, 22 and 23 and the lugs 15 not only permit the body sections 1a and 1b, the transverse bars 12, and the longitudinal bar 18 to be readily assembled and secured together but also materially aid the screws 13 and 19 in holding these parts firmly in assembled relation. The longitudinal bar portion 18a is provided with recesses

24 for the reception of clamps 25 which extend transversely of this bar portion. The recesses 24 are large enough to permit the clamps 25 to be adjusted longitudinally on the bar portion 18a. Screws 26 engaged with the clamps 25, and passing through slots 27 formed in and extending longitudinally of the bar portion 18a, function to secure the clamps to this bar portion for adjustment longitudinally thereof, and are adapted to be turned up to secure the clamps in their adjusted position.

The clamps 25 are provided with recesses 28 for the reception of the lateral sides of the bar portion 18a, and with recesses 29 for the reception of the neck of a violin, the recesses 28 establishing such a connection between the clamps and bar sections as to hold the former against any movement transversely of the latter, and the recesses 29 adapting the clamps to hold the violin neck against any lateral or upward movement with relation to the bar portion.

In practice, after the several parts of the form have been secured together, the neck 30 of the violin under construction is secured to the bar 18 by the clamps 25 with the upper block 31 of the violin positioned in the recess 8 of the form. The upper sides 32 of the violin are then applied to the neck 30, the block 31 and the upper convex edge 2 of the form. The lower block 33 of the violin is then positioned in the recess 9 of the form, and thereafter the lower sides 34 of the violin are applied to the block 33 and the lower convex edge 3 of the form. The corner blocks 35 of the violin are secured to the shoulders 5 of the form through the medium of adhesive paper strips 36 and thereafter the short center sides 37 of the violin are applied to the convex edge portion 4 of the form and to the blocks 35. The blocks 31, 33 and 35 are provided with glue prior to the application of the violin sides thereto. The upper sides 32 are held on the form by clamps which engage in the upper openings 7 and in the openings 10, and which contact with these sides, only one of these clamps being shown and designated 38 and the center is engaged by a clamp 39. The lower sides 34 are held on the form by clamps which engage in the lower openings 7 and in the openings 11, and which contact with the sides, only two of these clamps being shown and designated 40 and 41, respectively.

The clamps 38 and 40 are provided with blocks 42 which engage the sides 32 and 34 opposite the corner blocks 35, and the clamp 41 is provided with a block 43 which engages the sides 34 opposite the lower block 33. The sides 37 are held on the form by blocks 44 which engage the sides opposite the corner blocks 35, and by bars 45 positioned between the blocks 44. Prior to the application of the sides 32, 34 and 37 to the form, paper

strips 46 are applied to the edges of the form, and have their edges bent into contact with the opposite faces of the body 1, as shown in Figure 3. After the application of the sides 32, 34 and 37, the linings 47 of the violin are glued to the sides, and after the application of the linings, the back 48 is glued to the sides, the paper strips preventing the adhering of the linings to the form. The body 1 has a thickness less than the depth of the sides 32, 34 and 37 in order to permit the linings 47 to be applied to the sides. The transverse bars 12 and the longitudinal bar 18 are applied to the front side of the body 1 in order to permit the back 48 to be applied to the sides. To remove the assembled parts of the violin from the form, the screws 13 and 19 are withdrawn, and the screws 26 loosened. After this has been done, the clamps 25 which were moved downwardly on the violin neck 30 to retain it in place are moved outwardly on the neck, and after this has been done the bars 18 and 12 are removed from the body 1. The removal of the bars from the body 1 frees the body sections 1a and 1b for movement toward each other, and the body thus contracted may be readily withdrawn from the assembled sides and back of the violin. After the withdrawal of the form, the top of the violin is secured in place.

The adhesive strips 36 enable the corner blocks 35 to be readily freed from the form. The form may be made from wood or metal. When made from wood the corner blocks 35 will be secured thereon by the adhesive strips 36, and when the form is made from metal the corner blocks will be secured thereto by screws 49, as illustrated in Figure 8.

While I have described the principle of the invention, together with the structure which I now consider the preferred embodiment thereof, it is to be understood that the structure shown is merely illustrative and that such changes may be made, when desired, as fall within the scope of the invention as claimed.

What is claimed is:—

1. A gluing form for the upper, lower and center sides, the upper, lower and corner blocks and the neck of a violin, comprising a body having convex upper and lower edge portions and concave side portions to which the sides are to be applied, the body being provided at its upper and lower ends with recesses for the reception of the upper and lower blocks, and the body being provided between its convex edge portions and concave side portions with shoulders, means for removably securing the corner blocks to the shoulders, clamps for holding the sides in place, and means carried by the body and extending outwardly therefrom for holding the neck.

2. A gluing form for the upper, lower and center sides, the upper, lower and corner blocks

and the neck of a violin; comprising a body having convex upper and lower edge portions and concave side portions to which the sides are to be applied, the body being provided at 5 its upper and lower ends with recesses for the reception of the upper and lower blocks, and the body being provided between its convex edge portions and concave side portions with shoulders, adhesive strips for removably securing the corner blocks to the shoulders, 10 clamps for holding the sides in place, and means carried by the body for holding the neck.

3. A gluing form for the upper, lower and center sides, the upper, lower and corner blocks and the neck of a violin; comprising a body having convex upper and lower edge portions and concave side portions to which the sides are to be applied, the body being 15 provided at its upper and lower ends with recesses for the reception of the upper and lower blocks, and the body being provided between its convex edge portions and concave side portions with shoulders, and the body 20 being provided opposite said edge portions and shoulders with openings, means for removably securing the corner blocks to the shoulders, clamps engaged in said openings 25 for holding the sides in place, means carried by the body and extending outwardly therefrom for holding the neck, and clamps positioned between the ends of the center sides.

4. A gluing form for the upper, lower and center sides, the upper, lower and corner blocks and the neck of a violin; comprising a sectional body having convex upper and lower edge portions and concave side portions to which the sides are to be applied, the body being provided at its upper and lower ends 30 with recesses for the reception of the upper and lower blocks, and the body being provided between its convex edge portions and concave side portions with shoulders, means removably secured to the body sections for holding them in assembled relation with 35 their inner edges in spaced relation, means for removably securing the corner blocks to the shoulders, clamps for holding the sides in place, and means carried by the body and extending outwardly therefrom for holding the neck.

5. A gluing form for the upper, lower and center sides, the upper, lower and corner blocks and the neck of a violin; comprising 40 a sectional body having convex upper and lower edge portions and concave side portions to which the sides are to be applied, the body being provided at its upper and lower ends with recesses for the reception of the upper and lower blocks, and the body being provided between its convex edge portions and concave side portions with shoulders, 45 bars removably secured to the body sections for holding them in assembled relation with their inner edges in spaced relation, the bars 50

being recessed into the body sections and provided with lugs positioned between the inner edges of the sections, means for removably securing the corner blocks to the shoulders, 55 clamps for holding the sides in place, and means carried by the body and extending outwardly therefrom for holding the neck. 70

6. A gluing form for the upper, lower and center sides, the upper, lower and corner blocks and the neck of a violin; comprising a sectional body having convex upper and lower edge portions and concave side portions to which the sides are to be applied, the body being provided at its upper and lower ends with recesses for the reception of the 80 upper and lower blocks, and the body being provided between its convex edge portions and concave side portions with shoulders, means removably secured to the body sections for holding them in assembled relation 85 with their inner edges in spaced relation, means for removably securing the corner blocks to the shoulders, clamps for holding the sides in place, a bar secured to said first means and extending longitudinally beyond 90 the upper end of the body, and clamps carried by the upper end portion of said bar for engagement with the neck.

7. A gluing form for the upper, lower and center sides, the upper, lower and corner blocks and the neck of a violin; comprising a sectional body having convex upper and lower edge portions and concave side portions to which the sides are to be applied, the body being provided at its upper and lower 95 ends with recesses for the reception of the upper and lower blocks, and the body being provided between its convex edge portions and concave side portions with shoulders, means removably secured to the body sections for holding them in assembled relation 100 with their inner edges in spaced relation, means for removably securing the corner blocks to the shoulders, clamps for holding the sides in place, a neck supporting bar, 105 clamps supported outwardly of the body having recesses for the reception of the neck, and means securing the latter clamps to the upper end portion of said bar for adjustment 110 longitudinally thereon. 115

8. A gluing form for the upper, lower and center sides, the upper, lower and corner blocks and the neck of a violin; comprising a sectional body having convex upper and lower edge portions and concave side portions to which the sides are to be applied, the body being provided at its upper and lower ends with recesses for the reception of the upper and lower blocks, and the body being provided between its convex edge portions 120 and concave side portions with shoulders, transverse bars removably secured to the body sections for holding them in assembled relation with their inner edges in spaced relation, the bars being recessed into the body 125 130

sections and provided with lugs positioned between the inner edges of the sections, a longitudinal bar removably secured to the transverse bars and extending longitudinally beyond the upper end of the body, the longitudinal and transverse bars having interfitting recesses, and clamps for the neck secured to the upper end portion of the longitudinal bar.

13. In testimony whereof I hereunto affix my signature.

CHARLES J. AMUNDSON.
